UNITED STATES PATENT OFFICE.

JOHN R. THOMAS, OF CINCINNATI, OHIO, ASSIGNOR TO J. A. FAY & EGAN COMPANY, OF CINCINNATI, OHIO, A CORPORATION OF WEST VIRGINIA.

CHIP-BREAKER FOR WOODWORKING-MACHINES.

SPECIFICATION forming part of Letters Patent No. 700,257, dated May 20, 1902.

Original application filed May 29, 1901, Serial No. 62,413. Divided and this application filed December 23, 1901. Serial No. 87,022. (No model.)

To all whom it may concern:

Be it known that I, JOHN R. THOMAS, a citizen of the United States, residing in Cincinnati, in the county of Hamilton and State of Ohio, have invented certain new and useful Improvements in Chip-Breakers for Woodworking-Machines, of which the following is a specification.

This application is a division of my application for patent on improvement in molding-machines filed May 29, 1901, Serial No. 62,413.

The object of my invention is to provide a new and improved chip-breaker for wood-working-machines, whereby the pressure may be selectively directed to different points transversely of the cutter-head; and it consists in providing a pressure device for the chip-breaker arranged to be adjusted to different positions longitudinally of the cutter-head, and, further, in the parts and in the construction, arrangement, and combinations of parts hereinafter more fully described and claimed.

In the drawings, Figure 1 is an end elevation of my improved device shown in connection with adjacent parts of a woodworking-machine. Fig. 2 is a plan view of the same. Fig. 3 is an end elevation of my improved device partly in section for better illustration of parts. Fig. 4 is a side elevation of my improved device shown in raised position, and Fig. 5 is a detail in end elevation of the swinging arm for the same.

A represents the frame of the machine, in which a cutter-head B may be suitably journaled, and C represents a chip-breaker.

1 is a swinging frame having a bearing 2, taking about a rod 3, secured in lugs 4 to the frame of the machine. The frame 1 has a planed face 5 for receiving a similar planed end of a chip-breaker support 6, bolts 7 taking into the support through slots 8 in the swinging frame 1, and thereby affording adjustment of the same toward and away from the cutter-head. At its lower end the support carries a chip-breaker bar or foot 11, adjustable thereon to and from the cutter-head by means of having bolts 12 take through slots 13 in the support and screwing into the chip-breaker. The support carries a rod 15, upon

which a pressure-lever 16 is adapted to swing. The pressure-lever is also adjustable sidewise with relation to the chip-breaker bar, as by being slid on the rod, so as to exert the pressure, as from a weight 17, against any desirable point transversely of the chip-breaker. The pressure-lever preferably has a downward extension 18 and a rearward extension 19. A bolt 21 screws through the lever and is held firmly in place by means of a set-nut 22. A spring 23 preferably takes about the bolt between the lever and the support with the end of the bolt 21 normally held out of contact with the support by the spring, the spring thereby serving as a cushion between the pressure-bar or chip-breaker and the weight. A bolt 25, adjustable in the swinging frame, limits the downward movement of the chip-breaker by having the end of the bolt take against the frame of the machine.

My improved construction permits the chip-breaker to be swung upwardly and slid transversely out of the way, one or both movements being resorted to, as occasion may require. It also permits ready adjustment of the chip-breaker with relation to the cutter-head and, further, permits the pressure to be exerted at the point where greatest resistance is desired transversely of the machine by permitting the sidewise movement of the pressure agency.

I claim—

1. In a woodworking-machine, the combination with a cutter-head, of a chip-breaker therefor, and a pressure device for the chip-breaker, with means for permitting the sidewise movement of the pressure device transversely of the chip-breaker, substantially as described.

2. In a woodworking-machine, the combination of a chip-breaker, means for permitting the same to swing, a lever for the chip-breaker, a weight for the lever, a spring interposed between the lever and the chip-breaker, and means for permitting the sidewise movement of the lever with relation to the chip-breaker, substantially as described.

3. In a woodworking-machine, the combination of a chip-breaker, a swinging frame therefor, a rod for supporting the swinging

frame, means for permitting sliding sidewise of the swinging frame upon the rod, a weighting device for the chip-breaker, with means for permitting the sidewise movement of the 5 weighting device for exerting pressure from the weighting device upon the chip-breaker at different points across the latter, substantially as described.

In testimony whereof I have signed my name hereto in the presence of two subscribing witnesses.

JOHN R. THOMAS.
